UNITED STATES PATENT OFFICE.

FRANK L. MORSE, OF ITHACA, NEW YORK, ASSIGNOR TO MORSE CHAIN COMPANY, OF ITHACA, NEW YORK, A CORPORATION OF NEW YORK.

MACHINE FOR WEARING IN DRIVE-CHAINS.

1,255,912.

Specification of Letters Patent. Patented Feb. 12, 1918.

Application filed April 8, 1914. Serial No. 830,351.

To all whom it may concern:

Be it known that I, FRANK L. MORSE, a citizen of the United States, residing at Ithaca, in the county of Tompkins and State of New York, have invented a certain new and useful Improvement in Machines for Wearing in Drive-Chains, of which improvement the following is a specification.

In multi-plate drive chains wherein each 10 of the links is formed of a plurality of plates which are stamped or punched out of a sheet or strip of thin metal, and mounted on pintles to engage the teeth of the sprockets by a bearing upon the edge of said link plates, there may be a certain small amount 15 of stretching or lengthening during a short period of time after the chain is first put into actual service, due to the wearing down of minute projections upon the punched 20 surface of the bearing edges of the plates upon the pintles and upon the sprockets, and to other slight irregularities in the relative positions of the plates of a link upon the pindle. After the elimination of this initial 25 lengthening or stretching of the chain during the preliminary period of wear, the parts become firmly seated, and there is then very little or substantially no further lengthening or stretching during the 30 remainder of the useful life of the chain.

In some classes of work it is important that this initial stretching should be eliminated before the chain is put into actual service, and while this may be done by operating the chain under full load and actual service conditions for the necessary period of time, such method is objectionable since it requires a great amount of power and time to operate the drives under these conditions, while at the same time the useful life of the chain is shortened to a considerable degree, thus making the operation very expensive.

The principal object of my invention is to 45 provide an improved machine for working in drive chains to quickly and effectively eliminate the initial lengthening or stretching thereof without the expenditure of any material amount of power and without diminishing the useful life of the chain. In carrying out this idea, I provide driving and driven sprockets for a plurality of chains, the respective sprockets being fixed 50 relative to each other and there being an angular variation between two of said sprock-

ets such as to produce a tightening of the upper strand of one chain and the lower or opposite strand of another, or the other chain, whereby the drives are strained one against the other, and the forces are balanced so that, while the action of the link plates against the sprockets and upon the pintles is the same as when running under full load in actual service, the power required to operate the mechanism is merely 60 the amount necessary to overcome the friction of the moving parts. In this way the mechanism may be driven at a high rate of speed with very little power and the preliminary lengthening or stretching of the 70 chains will be rapidly eliminated as the link plates are subjected to the stresses of full load operation and are readily worn down to a permanent bearing.

The improvement claimed is hereinafter 75 fully set forth.

In the accompanying drawings: Figure 1 is a side elevation of a machine embodying my improvement; Fig. 2, a plan of the same; Fig. 3, a vertical longitudinal section; Fig. 4, a transverse section taken on the line 4—4 of Fig. 3; Fig. 5, a transverse section illustrating the relative position and angular variation of the two sprocket gears fixed upon the driving shaft; and Fig. 6, a 85 diagram illustrating the relative condition of the chains in two pair of chain drives.

According to the construction shown in the drawings: I provide a driving shaft, 14, mounted on bearings supported in journal boxes, 11, fixed upon a frame, 10, and having a plurality of sprocket wheels, 16 and 18, keyed on said shaft. One or more driven shafts, 15, having sprocket wheels, 17 and 19, are mounted parallel with driving shaft, 90 14, and in order that they may be movable toward and from the driving shaft, each of said driven shafts is mounted on bearings in journal boxes, 13, carried on a swingable frame, 23, pivotally mounted on the shaft, 12, in the sliding block, 24, supported in the guides, 25, on the main frame, 10. The swingable frame is provided with a downwardly extending arm, 26, which is connected by a link, 27, with the short arm of 105 lever, 28, pivoted on a bracket, 29, on the sliding block, 24, and having a weight, 30, adjustable upon its longer arm. With the sprocket chains, 20 and 21, applied to the respective pairs of wheels, 16, 17, 18 and 19, 110

it will be seen that the tension of the chains may be adjusted by shifting the weight, 30, on the lever, 28. A distance bar, 31, of the desired length is pivotally mounted on the 5 sliding block, 24, and bears against the fixed journal box frame, 11, to hold the shafts at the proper distance apart, according to the length of chain to be tested. When it is desired to apply or remove a 10 chain, the distance bar may be turned at right angles by means of a handle, 32, and the sliding block may then be moved toward the driving shaft to loosen the chain. The driving shaft may be driven in any suitable 15 manner, as by means of a belt and driving pulley, 22.

According to my improvement, the sprocket wheels upon one of the shafts, preferably the driving shaft, are fixed in such 20 positions relative to each other, that there is an angular variation between the sprocket teeth of one wheel, 16, and the sprocket teeth of the other wheel, 18, as indicated in Fig. 5, so that the teeth of the respective wheels 25 are not in line with each other, but are in an offset or staggered relation, the angular variation being some fractional part, preferably one-fourth to one-half, of the pitch of the sprocket teeth. The corresponding 30 sprocket wheels, 17 and 19, on the driven shaft are, however, fixed in such relative positions that their sprocket teeth are in line with each other and have no angular variation. If the teeth of the wheels on the two 35 shafts be staggered in the same relation there would then be no effective angular variation to exert a strain upon the drive chains, and the term "angular variation" as used herein is, therefore, understood to mean 40 the effective angular variation which would be the difference between angular relation of the teeth of the wheels upon one shaft, and the angular relation of the teeth of the wheels upon the other shaft. This effective 45 angular variation causes the upper strand of one drive chain, 20, and the lower strand of the other chain, 21, to be stretched tight while the opposite strands are loose. In this manner the two drive chains are strained 50 against each other, and the mechanism is balanced. When operated under this condition, the pressure and action of the link plates upon the pintles and sprocket teeth is substantially the same as when subjected 55 to full load in actual service, and as the resistance to movement is only that due to the friction of the moving parts, the machine may be readily driven at high speed with comparatively very little power.

60 When two or more drive shafts are employed, the sprocket wheels, 16 and 18, upon the driving shaft may be made wide enough to also accommodate the additional drive chains, such as 20^a and 21^a, or separate 65 wheels keyed in the proper relation may

be used, as indicated diagrammatically in Fig. 6.

For stopping the machine after the chains have been run the desired period of time, a brake, 33, may be employed, adapted to 70 bear upon the rim of the driving pulley, 22, and operated by shaft, 34, lever, 35, and spring, 36. The brake is normally held released by the lever, 35, bearing against the girder, 9, on which the frame, 10, of the machine is supported. When it is desired to stop the machine, the supporting rods, 8, are elevated by any suitable mechanism, thereby raising the frame, 10, and the entire machine above the girder, 9, a sufficient distance for the lever, 35, to clear the same, whereupon the spring, 36, throws the brake against the pulley, the belt for which is then slack, and the machine is quickly brought to a stop. The bars, 31, are then thrown over 85 to allow the sliding blocks and driven shafts to be moved toward the driving shaft a sufficient distance to loosen and remove the chains. New chains may then be placed upon the sprockets, the distance bars thrown 90 back into operative position, and the machine again started, the tension upon the chains during the process of stretching being regulated as desired by adjusting the weights, 30. By using several of these machines, a large number of drive chains may be quickly worn into the desired condition for actual service.

Having now described my invention, what I claim as new and desire to secure by Let- 100 ters Patent is:

1. In a machine for wearing in drive chains, the combination of a shaft having a plurality of sprocket wheels rigidly mounted thereon, another shaft having corresponding rigidly mounted sprocket wheels, chains on said sprocket wheels, one of the sprocket wheels on one of the shafts being deflected a portion of the pitch relative to 105 the teeth of another sprocket wheel on the same shaft and imparting a working stress to the opposite strands of the chains acting against each other, and means for driving 110 one of said shafts.

2. In a machine for wearing in drive 115 chains, the combination of a driving shaft, a driven shaft, and a plurality of pairs of sprocket wheels rigidly mounted on said shafts, chains on said sprocket wheels, the teeth of one of said wheels having an angular variation relative to another wheel 120 upon the same shaft to impart a working stress to the opposite strands of the chains acting against each other.

3. In a machine for wearing in drive 125 chains, the combination of a driving shaft, a pair of sprocket wheels fixed thereon, a driven shaft, a corresponding pair of sprocket wheels fixed thereon and chains on 130 said sprocket wheels, there being an effective

angular variation between the teeth of the respective pairs of sprocket wheels such as to produce opposing working stresses in the opposite strands of the chains.

5 4. In a machine for wearing in drive chains, the combination of a driving shaft, a driven shaft, and a plurality of pairs of sprocket wheels rigidly mounted on said shafts, and adapted to be connected by 10 chains, the teeth of one of said wheels having an angular variation relative to another, to subject opposite strands of said chain to opposing stresses, one of said shafts being movable toward and from the other, 15 and adjustable means tending to force said shafts apart.

5. In a machine for wearing in drive chains, the combination of a driving shaft, a driven shaft, a plurality of pairs of sprocket wheels fixed on said shafts, one of 20 said shafts having fixed bearings and the other movable, and a distance bar for spacing said shafts a certain distance apart.

6. In a machine for wearing in drive 25 chains, the combination of a driving shaft, a driven shaft, a plurality of pairs of sprocket wheels fixed on said shafts, one of said shafts having fixed bearings and the other movable, a sliding block supporting 30 the movable bearings, and a distance bar pivoted on said block for engaging the fixed bearing to space the shafts a certain distance apart.

7. In a machine for wearing in drive chains, the combination of a driving shaft, a driven shaft, a plurality of pairs of sprocket 35 wheels fixed on said shafts, the relation of the teeth of said wheels being such as to produce opposing working stresses in opposite 40 strands of the drive chains, one of said shafts

having fixed bearings and the other movable, a swinging frame for said movable bearing, and an adjustable weight for said swinging frame.

8. In a machine for wearing in drive 45 chains, the combination of a driving shaft, a driven shaft, a plurality of pairs of sprocket wheels fixed on said shafts, the relation of the teeth of said wheels being such as to produce opposing working stresses in the opposite strands of the drive chains, one of said 50 shafts having fixed bearings and the other movable, a swinging frame for said movable bearing, a pivoted lever attached at one end to said frame, and an adjustable weight 55 mounted on the other arm of said lever.

9. In a machine for wearing in drive chains, the combination of a driving shaft, a driven shaft, a plurality of pairs of sprocket 60 wheels fixed on said shafts, one of said shafts having fixed bearings and the other movable, a swinging frame for said movable bearing, a sliding block on which said frame is pivoted, a distance bar for said block, and an adjustable weight for said swinging 65 frame.

10. In a machine for wearing in drive chains, the combination of a driving shaft, a driven shaft, a plurality of pairs of sprocket 70 wheels rigidly mounted on said shafts and chains on said sprocket wheels, the relation of the teeth of said wheels being such as to produce a working stress in the opposite strands of the drive chains.

In testimony whereof I have hereunto set 75 my hand.

FRANK L. MORSE.
